PHOTOGRAPHIC PRINT-OUT MATERIAL HAVING A DESIGN THEREON

Joseph C. Ville, Rochester, N. Y., assignor, by
mesne assignments, to Eastman Kodak Com-
pany, Jersey City, N. J., a corporation of New
Jersey

Application July 26, 1935, Serial No. 33,348

14 Claims.

(Cl. 95—8)

This invention relates to photography and more particularly to a sensitive paper on which the design becomes visible or invisible under the action of light.

5 I have discovered that highly sensitive print-out paper may be used to indicate the action or the intensity of light by printing or forming a design on it with a solution of a desensitizer or a restrainer for the sensitive print-out compound.

10 Sensitive photographic emulsions in which a visible image is produced directly by the action of light are called print-out emulsions. They are ordinarily prepared by precipitating a halide of silver in a colloidal medium by interaction of a

15 solution of a soluble halide with a solution of a soluble compound of silver. If the emulsion is sensitized with silver chloride, the silver chloride is usually precipitated in such a way that the final product contains an excess of soluble silver

20 compound for example, silver nitrate, together with the silver salt of an organic acid and some of the free organic acid. These emulsions are not washed after the precipitation of the sensitive salt. A highly sensitive print-out paper which is suitable for the process of my invention is de-
25 scribed in Patent No. 2,030,860, granted February 18, 1936, to George E. Falleson and Cyril J. Staud.

In the accompanying drawing Fig. 1 is a flow-
sheet showing a plan view of a sensitive print-
30 out paper having a design formed thereon the
same color as the unexposed surface before and
after exposure;

Fig. 2 is a flow-sheet showing a plan view of a sensitive print-out paper having a design formed thereon of a color darker than that of the unexposed surface, before exposure, after partial ex-
posure, and after complete exposure.

In carrying out my invention I form a design on the surface of the sensitive print-out emulsion with a desensitizing or restraining compound. Under an action of light the sensitive portion of the print-out surface darkens and the portion treated with the desensitizer or restrainer is unaffected by the action of the light. I may include a dye with the solution of the desensitizing or restraining compound, but this is only for the purpose of increasing or decreasing the contrast between the sensitive and desensitized portions of the surface and is not absolutely essential.

50 Among the desensitizers or restrainers which are particularly useful in forming the design on the surface of the print-out emulsion, are thiourea and substituted thioureas; other organic sulfur compounds; the thiosulfates, such as sodium thio-
55 sulfate and other alkaline thiosulfates; alkaline

cyanides, such as sodium cyanide; alkaline thiocyanates such as potassium thiocyanate; alkaline halides such as potassium iodide and potassium bromide. Any suitable dye may be used, for example, a dye such as tartrazine or a mixture of tartrazine and malachite green. The desensitizing solution may be made up as follows:

Dye ..... 1 gram
Potassium bromide ..... saturated solution, 100 cc. 10
Water ..... 20 cc.

In one aspect of my invention the solution of dye and desensitizer or restrainer is made up so that the solution when printed, or otherwise placed on the sensitive paper in the form of a design, the design resulting when the solution is dried has the same color as the sensitive surface. This may be easily accomplished by selecting a dye of the same shade as the surface of the unexposed paper. When this paper is exposed to light for a few seconds the sensitive portion darkens and the desensitized design portion retains the original color. The design thereby becomes visible under the action of light. The appearance of the design takes place in a few seconds in moderate daylight when highly sensitized print-out paper is used. If the paper is held at a distance of about one foot from a 60 watt Mazda lamp, the image is clearly visible in about 20 seconds.

Another way in which my invention may be used is in the production of actinometer papers. In this case, the dye used in the restraining or desensitizing solution gives a color, when printed on the sensitive surface, which is slightly darker in shade than the unexposed emulsion. The dye may be such that the resulting design is a faint brownish shade and is clearly visible on the light greenish yellow background of the unexposed surface. When this paper is exposed to light, the unexposed background darkens and after a short time, depending on the intensity of the light, the design and the background merge, and the design becomes invisible. On further exposure the background continues to darken and the design once more becomes visible and is then a lighter color than the background. Paper treated in this way can be used to measure light intensity. The length of time required for the background and design to merge is dependent on the intensity of the light and is an extremely accurate way of measuring light intensity. The intensity of light may be measured more accurately with such paper than by comparing the darkening of print-out paper with paper of a standard shade placed beside it.

My invention will now be described with particular reference to the accompanying drawing in which the several figures are plan views of a paper made according to my invention, at various stages of exposure. In the modification shown in Fig. 1, 1 represents a sensitive print-out paper having a design 2 formed thereon with a solution of a desensitizer and a dye so that the design, when dried, has the same color as the unexposed background 1. On exposure the background 1 darkens as shown at 1a and the design 2 retains its original color and is readily apparent by reason of the contrast in color between it and the exposed background portion 1a.

In the modification shown in Fig. 2, in which the paper is used to measure the intensity of light, the design portion 3 is formed from a solution containing a dye of a darker shade than the unexposed surface 1. On exposure of this material to light, the background portion 1 will darken in color and the design portion 3 will retain the same color so that after a short time, as shown at 1b, the color of the background will be the same as that of the design, and the design 3 and the background portions will appear to merge. On continued exposure of this material to light the background portion 1b will further darken in color and there will again be a contrast between the background portion and the design portion of the paper as shown at 1c. Because of the contrast between the design portion and the background portion, in the unexposed and over-exposed condition, the intermediate exposure stage in which the design and the background portions merge is an extremely critical one and permits an accurate measurement of the time of exposure.

I have referred to "restraining" and "desensitizing" compounds. It is to be understood that by "restraining compounds" I mean those compounds which may not strictly be called "desensitizers" but which restrain the printing-out of the sensitive surface to such an extent that an image is formed very slowly or not at all. It is evident, therefore, that desensitizers are only powerful restrainers.

Other advantages and ways of employing sensitive paper treated in accordance with my invention will be readily apparent. The modifications described above are by way of example only and it is to be understood that my invention is limited only by the scope of the appended claims.

What I claim is new and desire to secure by Letters Patent of the United States is:

1. A light-sensitive silver salt print-out surface having a design formed thereon with a solution of a colored compound and a chemical restrainer for the printing out of the light-sensitive compound.

2. A light-sensitive silver salt print-out sur-

face having a design formed thereon with a solution of a dye and a chemical restrainer for the printing-out of the light-sensitive compound.

3. A light-sensitive silver salt print-out paper having a design formed thereon with a solution of a dye and a chemical restrainer for the printing out of the light-sensitive compound. 5

4. A light-sensitive silver salt print-out surface having a design formed thereon with a solution of a compound of the same color as the unexposed print-out surface and a chemical restrainer for the printing-out of the light-sensitive compound. 10

5. A light-sensitive silver salt print-out surface having a design formed thereon with a solution of a dye of the same color as the unexposed print-out surface and a chemical restrainer for the printing-out of the light-sensitive compound. 15

6. A light-sensitive silver salt print-out surface having a design formed thereon with a solution of a colored compound and thiourea. 20

7. A light-sensitive silver salt print-out surface having a design formed thereon with a solution of a colored compound and potassium iodide.

8. A light-sensitive silver salt print-out surface having a design formed thereon with a solution of a compound of the same color as the unexposed print-out surface and thiourea. 25

9. A light-sensitive silver salt print-out surface having a design formed thereon with a solution of a compound of the same color as the unexposed print-out surface and potassium iodide. 30

10. The method of making a light-sensitive photographic material which comprises forming a design on a light-sensitive silver salt print-out surface with a solution of a dye of the same color as the unexposed print-out surface and a chemical restrainer for the printing-out of the light-sensitive compound. 35

11. The method of making a light-sensitive photographic material which comprises forming a design on a light-sensitive silver salt print-out surface with a solution of a dye of the same color as the unexposed print-out surface and thiourea. 40

12. The method of making a light-sensitive photographic material which comprises forming a design on a light-sensitive silver salt print-out surface with a solution of a dye of the same color as the unexposed print-out surface and potassium iodide. 45

13. A light-sensitive silver salt print-out surface having a design formed thereon with a solution of a colored compound and a desensitizer for the light-sensitive compound. 50

14. A light-sensitive silver salt print-out paper having a design formed thereon with a solution of a dye and a desensitizer for the light-sensitive compound. 55
